UNITED STATES PATENT OFFICE.

LEO ALTER, OF CHICAGO, ILLINOIS, ASSIGNOR TO THE HARRY ALTER COMPANY, A CORPORATION OF ILLINOIS.

DESIGN FOR A TIRE.

Application filed December 18, 1928. Serial No. 29,321. Term of patent 7 years.

To all whom it may concern:

Be it known that I, LEO ALTER, citizen of the United States, residing at Chicago, in the county of Cook and State of Illinois, have invented a new, original, and ornamental Design for a Tire, of which the following is a specification, reference being had to the accompanying drawing, forming part thereof.

I claim:

The ornamental design for a tire as shown.

LEO ALTER.
